UNITED STATES PATENT OFFICE.

KARL ERIK WILHELM JAGDMANN, OF STOCKHOLM, SWEDEN.

BUILDING-BLOCK.

1,306,962.

Specification of Letters Patent. Patented June 17, 1919.

Application filed September 25, 1918. Serial No. 255,712.

To all whom it may concern:

Be it known that I, KARL ERIK WILHELM JAGDMANN, subject of the King of Sweden, residing at Rörstrandsgatan 58, Stockholm, Sweden, have invented certain new and useful Improvements in Building-Blocks, of which the following is a specification.

This invention relates to an improved form of block, adapted to be used in connection with floor and ceiling construction, together with an improved method of securing the same together.

Figure 1, in the accompanying drawings, is a sectional end elevation;

Fig. 2 is a sectional side elevation;

Fig. 3 a plan view;

Fig. 4 a sectional end elevation of a modified form of block; and

Figs. 5 and 6 details of construction adapted to be used in connection with the block illustrated in Fig. 4;

Fig. 7 is an end elevation, but showing a modified form;

Fig. 8 is a plan view of a number of blocks positioned together, without the use of reinforced metal; and

Figs. 9 and 10 are details of the grooved joints adapted to be used in connection with the structure illustrated in Fig. 8;

Fig. 11 a sectional view taken on the line 11—11 of Fig. 12;

Fig. 12 is a plan view; and

Fig. 13 illustrates a form of block which may be used without reinforced metal; and

Fig. 14 illustrates still another method of laying the blocks;

Figs. 15, 16, 17 and 18 illustrate blocks constructed of two or more pieces;

Fig. 19 is a slightly modified form of the construction illustrated in Fig. 18; and

Figs. 20, 21, and 22 illustrate details of construction to be used in connection with the reinforced bars.

Referring to the drawing, the floor consists of hollow blocks of concrete 1 which may be pressed mechanically in a factory or on the building place. The cavity may be divided by means of horizontal or vertical intermediate walls or filled up by a light substance. The blocks are provided with channels 2 into which the reinforcing metal 3 is inserted. Said channels may be made in the bottom and the four side surfaces of

the block, so as to form so-called cross-reinforcement. To produce a floor, a beam 4, preferably a wooden beam, is placed in parallel to one wall of the room, said wall, preferably being smoothed on a level with the ceiling, at a distance about corresponding to the length of a block. Preferably, the said beam is suspended by stirrups 5 in such manner that the upper edge is on a level with the smooth wall. Then a series of blocks is laid down, some mortar or packings being inserted between them. The joint surfaces may preferably be dipped into thin cement paste or any other binding or tightening material. Then the reinforcing metal is introduced into the channels. To retain said metal in place, iron plates 6 or the like may be provided, one for each joint or for some of them, preferably those common to two reinforcing metal rods. In order to receive the shearing stress said plates may be substituted by stirrups of round iron 9.

One or more reinforcing rods may be provided for each line, two of them are, however, to be preferred. The plates and, if desired, the stirrups are forced into the joints. To facilitate this operation recesses may be made in the blocks. The reinforcing metal is to be protected against rust by means of cement paste or in any other well-known manner. The ends of the rods are threaded and provided with nuts or any other locking device, so as to be capable of being tightened, for instance by means of wedges or eccentrics. The nuts having been tightened, the floor supports itself, and the beam is moved a distance corresponding to the length of a block. In this manner the lines are constructed one after another. In order to increase the connection of the floor and facilitate the construction thereof, the sides of the blocks are provided with groove-joints, such groove-joints being preferably also disposed in the joint-surfaces. The groove-joints may, if desired, be omitted altogether. The floors may also be provided with coherent plates.

The beam may be placed on the smoothed surface of the wall and cantalivered on a level with said surface. Such a construction is shown in Figs. 4 and 5, the beam being provided with a cantaliver 10 support

ing the blocks. The beam may be made of iron throughout having in such case the shape of an angle iron. This embodiment is shown in Fig. 6.

5 It is to be noted, that the beam may be omitted, if the reinforcing rods have their ends firmly secured to the side walls. This may, however, be used advantageously only in case of very small spans, because in 10 greater spans the rods are liable to be bent and, consequently, the floor will become swayed at the middle.

The blocks may also be fixed together. Contrary to the common floors such floors 15 may be built up in frosty weather, because the cement is already hardened, and it does not matter if the joints freeze.

Preferably, a cross-reinforcement is disposed in the middle of each floor.

20 The blocks may also be so molded as to have an aperture at one side only (Fig. 3) thus forming cross-beams 8, the supporting concrete beams being placed not only in the transverse but also in the longitudinal 25 direction of the blocks.

The cavities of the blocks may be filled with a sound-proof material, as for instance turf.

Such a method is illustrated in Fig. 7 of 30 the accompanying drawings showing three lines of connected blocks.

The different blocks are designated by 1, the channels or apertures for the reinforcing metal by 2. According to Fig. 7 each 35 block is connected with the preceding line by clamps 3 which, after the reinforcing metal has been tightened, may be removed.

Another method of laying out the blocks without molds or beams and gripping reinforcing metal is shown in Fig. 8. The 40 method consists in providing the blocks with groove-joints in such a manner that the blocks in the first line rest on the supporting wall or the like, the blocks in the second line 45 on the first line, the blocks in the third line on the second line and so on. A form of the groove-joints suitable in this case is shown in Figs. 9 and 10, being sectional views on lines 9—9 and 10—10 respectively in Fig. 8.

50 A further manner of performing such a method is shown in Figs. 11 and 12, Fig. 12 showing some lines viewed from above and Fig. 11 a section on line 11—11 in Fig. 12. According to this method the 55 blocks are joined together in such manner that each second or third block, etc., of the first line consists of two quartered blocks resting against the wall, a reinforcing rod 11 being introduced in apertures 12 made in the blocks. Then usual 60 blocks are inserted in the interspaces between the two quartered blocks, the usual blocks resting, on the one hand, against the wall and on the other hand against the reinforcing rod 11. To this purpose the usual blocks 65

are provided with channels or grooves 13 in the lower side. Then another reinforcing rod is introduced in apertures 14 in the usual blocks, said rod serving in turn as support for another line of usual blocks and so on. 70

Such a mounting of the blocks on the reinforcing metal may be avoided, if the blocks be provided with groove-joints, as shown in Fig. 13. In this case the groove-joints are indicated by 15, and it will appear distinctly 75 from the figure that the blocks of each subsequent line are placed on the joints of the blocks in the next lower line. In this case the reinforcing metal may be introduced, after the lines of blocks are laid out. 80

Fig. 14 shows still another method of laying out the blocks. In this case the blocks are preferably wedge-shaped to a certain extent. The blocks are introduced or forced in between the blocks previously laid out or 85 reinforced.

This method is to be used in case of the reinforcing metal being provided with rivet heads, hooks or the like and tightened by widening the lines of blocks. 90

In the practical use the blocks hereinbefore described have not proved quite satisfactory. Thus in case of great spans or heavy loads in which case the blocks are very great and heavy it has proved to be of 95 advantage to use blocks open at the bottom and provided with a false bottom preferably made of lighter material or to divide each block in two or more parts. The false bottom may also be omitted in which case 100 the beams are visible from beneath or concealed by plastering or the like.

It is to be noted that the upper portion of the blocks ought, in general, to be of greater size than the lower portion, for instance 105 twice as great, because the upper portion has to receive the greatest stresses.

Some embodiments of blocks produced according to the invention are shown in Figs. 15 to 22 inclusive. 110

In Fig. 15 the block is U-shaped, a false bottom 16 of lighter or cheaper material being provided.

Fig. 16 shows a modified form of the block in Fig. 15, each block consisting of two 115 halves.

In Figs. 17, 18 and 19 the blocks are divided into T-shaped portions or in any other manner.

The blocks shown in Figs. 20, 21 and 22 are 120 characterized by channels 18 leading to the apertures 2 for the reinforcing metal and serving for the filling in of the cement paste or the like. Said channels may be made in the material or in form of grooves in the 125 joint surface.

It is to be noted that, if the apertures are provided with connecting channels, one vertical channel only is needed for each block.

Obviously, the grooves may be replaced by 130

apertures 2 if conditions permit that the reinforced metal may be threaded through such apertures.

Claim:

- 5 A floor construction including a number of blocks provided with male and female ends so that such blocks may interengage, said blocks being provided with a groove below each of their interengaging portions and
- 10 above their lower edges, reinforcing rods

passing through the grooves of a number of blocks and plates encircling the rods and being positioned in a recess formed in each of the blocks.

In testimony whereof I affix my signature 15 in presence of two witnesses.

KARL ERIK WILHELM JAGDMANN.

Witnesses:

FRITZ E. HALLIN,
GRETA PREN.
